TAKE-APART PUZZLE

Irving Hartley Steinhardt, New York, N. Y.

Application October 26, 1949, Serial No. 5,707

Term of patent 14 years

(CL. D34—15)

To all whom it may concern:

Be it known that I, Irving Hartley Steinhardt, a citizen of the United States, residing at New York, in the county of New York, and State of New York, have invented a new, original, and ornamental Design for a Take-Apart Puzzle, of which the following is a specification, reference being had to the accompanying drawing, forming part thereof.

In the drawing:

Fig. 1 is a front view of a take-apart puzzle, showing my new design;

Fig. 2 is a side view thereof;

Fig. 3 is a rear view thereof; and

Fig. 4 is a top view thereof.

The essential features of my design reside in the parts shown in full lines.

I claim:

The ornamental design for a take-apart puzzle, substantially as shown, and described.

IRVING HARTLEY STEINHARDT.
